Jeremiah D. Green and George Warren Design for Cooking Stoves

Patented April 16 1850

Design No. 280.

DES 280

*Stoves and Furnaces,
Cooking Stoves and Range*

FIG. 2

FIG. 1.

Des. 280

Jeremiah D. Green & George Warren of Troy N. Y.
Letters Patent No. 280. Dated April 16. 1850.

The Schedule referred to in these Letters Patent and making part of the same.

So all whom these presents shall come:

Be it known that we Jeremiah D. Green, and George Warren of Troy, in the County of Rensselaer, and State of New York, have invented or produced a new and original design of Cooking Stove which we call the "Prize Premium", and we do hereby declare that the following is a full, clear, and exact description of the same, reference being had to the annexed drawings, which make a part of this specification, in which fig. 1. is a side elevation of the whole stove, and fig. 2. a view of the front plate detached from the other parts of the same.

Our stove is in the form of that well known as the "Prize Premium", so shaped in its mouldings, panels, and ornament as to constitute a new design of ornament and configuration.

In the front there are double doors, which I have not represented in the drawing, they being the same in the figure of ornament and shape as the side door A. and is not deemed necessary to be repeated, the stove in main is plain, the edges of the top and bottom being formed of heavy mouldings projecting out beyond the other parts of the stove. The doors consist of mouldings around the edges, so as to form a panel within them, which is ornamented with arabesque figures B. B. the front besides the doors above described

Des. 288

324

contains three panels, one c. c. situated at each side of the doors, and one D, over the doors, with the title of the stove cast thereon.

The stove is supported on feet E. E. ornamented with voluted border scrolls a. a, within which are arabesque figures b. b.

What we claim as our new design, and desire to secure by Letters Patent, is the design and configuration of ornaments in the panels of the doors, and on the feet so as to constitute in combination a new design of Cooking Stove, as herein described and represented.

Witnesses.
